G. P. MARTINELLI.

NEEDLE THREADER.

APPLICATION FILED JULY 5, 1916.

1,277,741.

Patented Sept. 3, 1918.

Fig. 1.

A technical line drawing of a harp's neck and soundboard. The neck, labeled 14, is a vertical column with a curved top. A soundboard, labeled 11, is attached to the neck. A tuning pin, labeled 9, is shown at the top of the neck. A decorative scroll, labeled 8, is at the top of the neck. A label 15 points to a small circular hole. A label 10 points to a slot or slot-like feature. A label 18 points to a curved part of the neck. A label 5 points to a small circular hole on the soundboard. A label 19 points to a small circular hole on the soundboard. A label 20 points to a slot on the soundboard. A label 21 points to a slot on the soundboard. A label 16 points to a slot on the soundboard. A label 22 points to a slot on the soundboard. A label 23 points to the base of the neck.

UNITED STATES PATENT OFFICE.

GUIDO P. MARTINELLI, OF NEW YORK, N. Y.

NEEDLE-THREADER.

1,277,741.

Specification of Letters Patent.

Patented Sept. 3, 1918.

Application filed July 5, 1916. Serial No. 107,615.

To all whom it may concern:

Be it known that I, GUIDO P. MARTINELLI, a subject of the King of Italy, residing at New York, in the county of New York and 5 State of New York, have invented certain new and useful Improvements in Needle-Threaders, of which the following is a specification.

This invention relates to needle threading 10 devices for use in connection with sewing machines, and aims particularly to improve and generally increase the efficiency of devices of this character.

A further object of the invention is to 15 provide a device for this purpose which may be permanently attached to the needle bar of the machine and which will not interfere with the operations of the machine.

A still further object of the invention is 20 to provide a mechanism of the above described character which is of simple and inexpensive construction, which is composed of but few simple and readily assembled parts, which is capable of being readily attached to various types of machines, which 25 has its parts so assembled and constructed as to preclude wear, breakage or derangement of the same, and which may be moved to an out of the way position during the 30 operation of the machine.

With these objects in view, together with others which will appear as the description proceeds, the invention resides in the novel formation, combination and arrangement of 35 parts, all as will be described more fully hereinafter, illustrated in the accompanying drawings, and particularly pointed out in the claims.

The invention will be best understood by 40 reference to the accompanying drawings, wherein:—

Figure 1 is a fragmentary side elevation of a conventional form of sewing machine head and needle bar, and illustrating the application of a threading device constructed 45 in accordance with the invention;

Fig. 2 is a detail perspective view of the threading device removed from the machine bar; and

Fig. 3 is a similar view of the threading arm support.

Referring now more particularly to the drawings, 3 indicates the machine head, within which the needle bar 4 reciprocates in 55 the usual manner. A needle 5 of conventional form is secured to the lower end of

the needle bar, the same being held by the block 6.

Secured to the needle bar 4, as by a screw 7 is a threader arm supporting member 8. 60 This member is preferably of L-shaped construction as shown, and has an angularly disposed ear 9 upon the upright portion of the same by means of which the said member is fastened to the needle bar. The horizontally disposed portion of the member 8 is slotted as at 10 inwardly from one end to provide a spring portion 11, the latter having a lug 12 at its extremity. The opposite end of the horizontally disposed portion is 65 provided with an aperture 13.

The threader arm 14 is pivoted at one end as at 15 to the member 8, the pivot pin extending through the opening 13. This arm is provided at its lower end with an angularly disposed foot 16, and a back plate 17. The back plate is cut away as at 18 at its juncture with the threader arm to provide a thread guide. A block 19 is arranged upon the threader arm at the foot portion 80 thereof, and has one face alining with one wall of the thread slot 18. Secured upon this block by means of screws 20 or other suitable securing elements is an angular plate 21, the outer face of which is disposed 85 in the same plane with the thread slot 18. This portion of the plate is provided with an opening through which a thread hook 22 extends. A backing element 23 may be arranged adjacent the outer edge wall of the 90 guide slot 18 to facilitate engagement of a thread inserted through said slot with the hook 22.

The threader arm 14 is of such length as when swung to downward position, as indicated in Fig. 1 of the drawings, to aline the hook 22 at the foot end thereof with the eye of the needle 5. This hook is of such small dimension as will enable the same to extend through the needle eye without engaging the walls thereof, and it is apparent that when in the position indicated in Fig. 1 and a thread is inserted into the guide slot 18 and engaged with the hook 22, rearward swinging movement of the said arm will 105 draw the thread held by the hook through the needle eye. When the thread has thus been drawn through the needle eye, the same may be detached from the hook, and the arm 14 swung upwardly into the position indicated by dotted lines in Fig. 1. When in this latter position, the lug 12 will snap

under the foremost edge of the bar 14, whereby the latter is held against downward movement.

From this description, it is apparent that I have provided a simple and efficient means for attaining the ends set forth. The device is capable of being readily swung to such position as not to interfere with the sewing operation of the machine. The means for supporting the threader arm in upward position is capable of being easily manipulated to lower the arm when required. It is also apparent that other changes in the minor details of construction and arrangement of parts may be resorted to if desired, without departing from the spirit of the invention or exceeding the scope of the claims.

What is claimed is:—

1. A needle threading attachment for sewing machines including a plate split longitudinally to define a pair of spring tongues connected at one end, means for rigidly connecting one tongue to the needle bar of the machine, a beveled lug on the other tongue, an arm pivotally mounted on the connected end of the plate, and a thread-

ing means carried by the arm, said arm being movable from a position adjacent the needle, to a position wherein it is engaged over the lug which acts to retain the arm in place.

2. A needle threading attachment for sewing machines including a plate for connection to the needle bar of the machine, an arm pivotally mounted on the plate for movement toward and away from the needle, a diverging member in the plane of the arm and formed upon the terminal thereof to form a thread guide, a laterally extending plate carried by said terminal of the arm, a block carried by the plate, an angular plate mounted on the side of the block, and a hooked threading member carried by the angular plate and intersecting the space between the arm and diverging member.

In testimony whereof I affix my signature in presence of two witnesses.

GUIDO P. MARTINELLI.
